UNITED STATES PATENT OFFICE.

JOHN KINGSBURY WEST, OF DETROIT, MINNESOTA.

PROTECTIVE DEVICE FOR RAILWAY CROSSINGS.

Application filed May 11, 1925. Serial No. 29,527.

My invention is a protective device for railway crossings of the type which affords facilities for operating a gate which is positioned adjacent to the crossing, and it has 5 the combinations, constructions, and arrangements herein described.

An object of the invention is the provision of a device of the character described which has means operable by a railway car approaching the crossing on a track of the crossing to move a gate to position to obstruct passage onto the track and operable by the railway car as it passes over the crossing to open the gate when the car has passed 15 the crossing.

A further object of the invention is the provision of a device of the character described which is reliable in use, not likely to get out of order easily, and thoroughly practical commercially.

A still further object of the invention is the provision of a device of the character described which has means operable automatically to sound an alarm when the gate 25 at the railway crossing is closed.

A still further object of the invention is the provision of a device of the character described which can be applied to a railway crossing without any extensive changes, if 30 any, in the usual railway track construction being required.

Other objects and advantages of the invention will be apparent from the following description considered in connection with 35 the accompanying drawings in which:

Figure 1 is a plan view of my improved device associated with a railway crossing.

Figure 2 is a view showing in vertical section a portion of the highway bed of the 40 crossing and a housing and supporting structure which the invention provides and showing in elevation a gate comprising a pair of vertical swingable arms and an arrangement that the invention provides for operating the gate arms.

Figure 3 is a plan view of the structure that is exhibited in Figure 2.

Figure 4 is a fragmentary view showing in vertical section a portion of the track bed 50 and showing in elevation a portion of the track rail, and a switch mechanism which is associated therewith;

Figure 5 is a transverse vertical section through the structure exhibited in Figure 4,

Figure 6 is a fragmentary vertical section

similar to Figure 5, showing a second form of switch that the invention embodies and

Figure 7 is a view showing more or less diagrammatically certain of the elements of the device and typical circuits which may be 60 provided.

Referring now to Figure 1, I show a crossing which is formed by the intersection of a highway 1 for vehicular or other traffic and a railway track 2. The invention contemplates the positioning of a pair of gates at opposite sides of the track 2 in positions to obstruct passage along the highway onto the track when the gates are closed and to permit passage along the highway across the 70 track when the gates are open. Each of these gates may comprise a pair of vertically swingable arms 3 having the inner end portions thereof extended through vertical slots 4 in opposite side walls 5 of a supporting 75 and housing structure generally indicated at 6, the inner ends of the gate arms terminating in vertical enlarged portions 7 within the chamber 8 that the housing structure defined. These inner end portions 7 of the 80 gate arms are supported on horizontal pivot elements 9 which are located in the upper part of the chamber 8 and which extend parallel to the highway 1 and substantially at right angles to the portion of the track 85 2 which crosses the highway. The housing structure 6 may be formed of concrete or any other suitable material and is positioned in the middle of the highway adjacent to one side of the track 2, it, of course, being understood that there is a housing structure 6 at each of the opposite sides of the track. The gate arms 3 therefore will be supported by the pivot elements 9 in position to obstruct 90 passage along the highway 1 at both sides of the structure 6 onto the track 2 when the gate arms have been swung downwardly in opposite directions in the slots 4 to positions to extend laterally on opposite sides of the housing structure 6 from the middle portion 95 of the highway to the side edges thereof. When the gate arms are in the passage-obstructing position just described and are substantially horizontal, the outer ends of the arms will rest in notches or slots 10 in the upper ends of posts 11 which are located at opposite sides of the highway.

The enlarged inner end portions of the arms 3 are pivotally attached by horizontal pivot elements 12 to the upper ends of con- 110

necting rods or links 13 which are pivotally attached at their lower ends to a wristpin 14 which is carried by a crank disc 15. The connection of each link 13 with an inner 5 end portion of a gate arm 3 at a level higher than that of the pivot element 9 on which that particular gate arm is supported when the gate arm is in substantially horizontal position as shown in Figure 2, and at this 10 time the wrist pin 14 will be positioned at the highest part of its path of movement. Therefore, when the crank disc 15 is rotated about its axis through 180° from the position shown in Figure 2, the gate arms 3 will 15 be actuated to cause the outer end portions thereof to swing upwardly until these gate arms are substantially vertical, slots 16 which are formed in the covering 17 for the housing structure 6 in alignment with the 20 slots 4 permitting this upwardly swinging movement of the gate arms. When the rotation of the crank disc is continued through the remainder of a complete rotation, the gate arms will be swung downwardly in the 25 slots 16—4 from substantially vertical and non-obstructing positions to substantially horizontal, active, or passage-obstructing positions.

The crank disc is secured on a horizontal 30 shaft 18 which is supported in the chamber 8, as by means of a pin 19 at the upper end of a supporting standard 20 on the floor of the chamber 8 so that the axis of the shaft 18 is parallel to the axes of the wrist pin 14, 35 the pivot elements 12, and the pivot elements 9.

Rotation of the shaft 18 to operate the gate arms 3 in the manner just described may be effected by any suitable driving 40 means. I prefer to use a drum 21 which is secured on the shaft 18 within the chamber 8. Cable 21' is secured at one end to the periphery of the drum and after being passed a plurality of times about the periphery of the drum is attached at its other end to a weight 22. The weight 22 will be supported in elevated position close to the drum 21 when the cable is practically completely wound on the drum and gravity will tend to cause downward movement of the weight 45 from such elevated position. A pit or cavity 23 may extend downward from the bottom of the chamber 8 to permit a relatively great vertical movement of the weight 22. This downward movement of the weight 22 will cause the cable to be unwound from the drum and at the same time will turn the drum and the shaft 18 about the axis of the shaft, also turning the crank 50 disc 15 and operating the gate arms. Rotation of the shaft in respect to the actuation of the weight 22 is controlled by means which will now be described. Such means 55 comprise a control disc 24 which is secured on the shaft 18 and is formed with stop projections 26 and 25 respectively. These stop projections extend radially outward from the periphery of the disc 24 and are spaced 180° apart. The stop projections 25 and 26 are out of alignment with each other, one 60 stop projection being adjacent to one edge of the periphery of the disc 24 and the other stop projection being adjacent to the opposite edge of the periphery of the disc 24. As shown in Figure 3, a pair of electro-magnets 70 27 and 28 respectively are positioned in the chamber 8 in side by side relation so that the armature 30 of the electro-magnet 28 will lie in the path of movement of the stop projection 25 when the electro-magnet 28 is de-energized and the armature 29 of the electro-magnet 27 will lie in the path of movement of the stop projection 26 when the electro-magnet 27 is de-energized. When the electro-magnets are energized the armatures 80 thereof will be retracted into the casings of the electro-magnets out of the paths of movement of the respective stop projections 85 25 and 26.

The invention provides a means controlled by the wheel of a railway car which transverses the track 2 for energizing the electro-magnets 27 and 28. Such means comprise a pair of normally open electric switches generally indicated at 31 (see Figures 4 and 5) for the electro-magnet 28. The respective switches 31 are positioned at opposite sides of the highway at considerable distances from the highway and in proximity to one of the rails of the track. 90 Each switch 31 comprises a switch casing 32 which is embedded in the track bed 33 underneath the flange of the track rail so that a vertically-moving actuating rod 34 may extend alongside of the track rail through 95 aligned vertical slots 35, 36, and 37 in a guide block 38, the top 38' of the switch case, and the base flange of the rail, respectively. The upper end portion of the actuating rod 100 34 extends at one side of the head of the rail nearly to the level of the top face of the latter when a vertically swingable arm 39 on which the lower end of an actuating rod 34 rests is substantially horizontal, as shown 105 in Figure 5. The arm 39 is pivotally supported at one end on a horizontal pivot element 40 and is pivotally attached adjacent to its other end as at 41 to a rod 42 which extends slidably through a central opening 110 in the head 43 of a cylinder 44 and is secured at its lower end to a piston 45, which is reciprocable in the cylinder 44. The latter is secured to the bottom of the case 32, preferably pivotally as at 46, so that the cylinder 44 is capable of limited swinging 115 movement about an axis parallel to the pivot element 40. An expansion spring 47 is disposed about the rod 42 and reacts at one end against the head of the cylinder 44 and at 120 the opposite end against the arm 39, thereby 125 130

tending to maintain the arm 39 in horizontal position as shown in Figure 5. The piston 45 may be formed with one or more vertical openings as indicated at 48, each of these openings being controlled by an upwardly opposing check valve. The free end of the arm 39 rests on the free end portion of a spring contact 50, which is supported at its other end on a vertical wall of the switch case 32 directly above the corresponding end of stationary contact 51. The inherent resiliency of the spring contact 50 acts to maintain the spring contact 50 out of contact with the contact 51. However, it is manifest that downward movement of the actuating rod 34 will cause the arm 39 to swing downward against the action of the spring 47, thereby forcing the free end portion of the spring contact 50 downward against the action of the spring 47, thereby forcing the free end portion of the spring contact 50 downward against the stationary contact 51. This downward movement of the actuating rod 34 will take place when the wheel of a railway car traverses the track rail, since the open end of the actuating rod 34 normally extends alongside of the head of the track rail high enough to be engaged by the flange of the wheel which traverses the rail. The downward movement of the arm 39 will also cause downward movement of the piston 45 in the cylinder 44, the valves opening during the downward movement of the piston and then closing and thereby retarding or diminishing the return or downward movement of the piston. Therefore, the first wheel of a train which traverses the track will force the actuating rod 34 downward and the valve piston will act to retard the return or upward movement of the actuating rod so that such rod will be actuated by the wheels of a train but very few times during the passage of a train of considerable length along the track.

In Figure 6 I show a normally closed switch, generally indicated at 31', which differs from the switch that is exhibited in Figures 4 and 5 only in certain details which will now be set out and which is operated by a mechanism identical with the hereinbefore described mechanism that the invention provides for operating the switch 31. The operating mechanism for the switch shown in Figure 6 therefore is only partly illustrated and such parts thereof as are shown have been indicated by the same reference characters primed as were used to designate corresponding parts of the operating mechanism of the switch shown in Figures 4 and 5. The switch exhibited in Figure 6 comprises a stationary contact 52 which extends inwardly from the wall of the case 31' downward to the free end of the vertical swingable arm 39'. A movable spring

contact 53 is secured at one end to the same wall of the case 31' directly beneath the contact 52 and extends within the case 31' in contact with the contact 52 so that the free end of the spring contact 53 terminates underneath and against the free end portion of the vertically-swingable arm 39'. Therefore, it will manifest that downward movement of the free end portion of the arm 39' will move the spring contact 53 out of engagement with the stationary contact 52. This downward movement of the arm 39' is effected in the same manner as downward movement of the arm 39, or, in other words, as the result of the downward movement of a vertically-moving rod actuating the swingable arm 39', such downward movement of the actuating rod being caused by the flange of the wheel of a railway car which traverses the rail with which the case 32' is associated.

By referring to Figure 7, it will be understood that two of the switches 31 respectively are positioned adjacent to one of the rails of the track at opposite sides of the highway 1 and that two of the switches 31' are associated with the same track rail as the switches 31, each being positioned adjacent to a closed switch 31, being between the latter and the highway. An additional switch, indicated at 54, is identical in construction with each of the switches 31 and therefore has not been illustrated in detail in the drawings. This switch 54 is positioned midway of the highway and adjacent to the track rail so that the flange of the front wheel of a railway car passing along the track across the highway 1 actuates the operating mechanism of the switch 54 to close the switch 54 for a purpose to be presently stated.

The contacts 50 of the switch 31 are connected by conductors 55 with conductor 53, which leads to one end of the electro-magnet 28. The movable contacts 51 of the switches 31 are connected by electric conductors 58 to the contacts 53 of the switches 31'. The stationary contacts 52 of the switches 31' are connected by conductors 59 with a conductor 60 which leads to one side of a battery 57. The stationary contact of the switch 54 is connected by an electrical conductor 61 to one end of the coil of one of the electro-magnets 27. The movable contact of the switch 54 is connected by a conductor 62 with the conductor 60 which leads to the hereinbefore mentioned side of the battery 57. The second end of the coil of the electromagnets 27 is connected by an electrical conductor 63 with a conductor 64 which leads from the second end of the coil of the electro-magnet 28 to the second side of the battery 57. The electro-magnet 28 at the opposite side of the track 2 is connected electrically in series with the said first electromagnet 28 by means of an elec-

trical conductor 65 which leads from one end of the coil of the second electro-magnet 28 to one side of a battery 66. An electrical conductor 67 leads from second side of the 5 battery 66 to one of the electric conductors 55. An electric conductor 68 leads from the second end of the coil of the second electro-magnet 28 to the conductor 59. In a like manner the second electro-magnet 27 is 10 connected electrically in series with the first electromagnet 27 by electrical means, which include an electric conductor 69 leading from end of the coil of the second electro-magnet 26 to the conductor 65 and an 15 electric conductor 70 which leads from the second end of the coil of the second electro-magnet 27 to the electric conductor 62.

From the foregoing description of the various parts of the device, the operation 20 thereof may be readily understood. The foremost wheel of a car or train approaching the highway 1 from either of the two opposite directions from which movement is possible along the track 2 will actuate the 25 operating mechanism of the adjacent switch 31 and will close the circuit which has been described in detail for energizing the electro-magnets 28. Energization of these magnets will cause retraction of the armatures 30 and the control discs 24 being permitted to rotate through 180° from the position shown in Figure 7 thereby permit rotation of the shafts 18 in response to the actuation of the weight 22 through 180° and cause the 35 gate arms of the gates at opposite sides of the track to move from raised, inactive positions to lowered, passage-obstruction positions as shown in Figure 2. The operating mechanism of the adjacent switch 31' will 40 be actuated to break the circuit shortly after one of the switches 31 has been closed. At this time the switch 54 will be open, that being the normal condition of that switch and the armatures of the electro-magnets 27 will 45 be in extended positions. The control discs 24 having rotated through 180° from the positions shown in Figure 7, the armatures of the electro-magnets 27 will engage with the stop projections 26 and will prevent further movement of the shafts 18, whereby the 50 gate arms will remain in lowered, active positions until the foremost wheel of the car or train which is traversing the track 2 has passed along the track onto the crossing and to position to actuate the operating 55 mechanism of the switch 54. Actuation of the operating mechanism of the switch 54 will cause closing of the latter and of the circuit it controls. Energization of the electro-magnets 27 will be effected. The armatures 29 which will be retracted from the 60 position shown in Figures 2 and 3 and the control discs 24 will be released for rotation through 180°, thus causing the gate 65 arms to be swung from lowered, active posi-

tion to raised, inactive position. After the car or train has passed the crossing, the foremost wheel thereof will engage with the second switch 31' before engaging with the second switch 31, thereby preventing 70 closing of the circuit for operating the electro-magnets 28 by the train or car which has crossed the highway and moves on the track 2 away from the railway crossing. It may 75 be desirable to sound an alarm at the time the gate arms 3 are lowered to active position. I therefore may place any suitable alarm, such as indicated more or less diagrammatically at 71 in Figure 2, in each or only one of the chambers 8. This alarm may 80 be of any suitable known construction but preferably is of the type which includes an operating mechanism, (not shown), such as may be found in an ordinary alarm clock, said operating mechanism being prevented 85 normally from sounding an alarm by a movable spring-impelled control member 72. An arm 73 for operating the control member 72 is pivotally supported intermediate its length so that the upper end portion 90 thereof extends in the path of movement of a stop projection 74 when the latter moves through 180° from the position shown in Figure 7. In other words, the upper end of the pivoted arm 73 will be engaged by the 95 stop projection 74 shortly after the stop projection 25 has been disengaged by the associated armature 30. The resulting movement of the arm 73 will actuate the control member 72 to release the means for 100 sounding an alarm and an alarm therefore will be sounded each time the gates are closed.

The operating mechanism will be well 105 protected from the weather and from accidental injury and is not likely to get out of order easily. When the weight 22 which is associated with each of the shafts 18 has moved to the limit of its downward stroke it may be raised to permit rotation of the 110 drum and shaft to re-wind the cable on the drum. It is obvious that other driving mechanism of known construction may be employed to rotate the shaft continuously in one direction when the control disc 24 115 has been released without involving any departure from the spirit and scope of the invention.

Obviously, the invention is susceptible of 120 modifications and adaptions from the form of the device that is illustrated in the accompanying drawings and I therefore consider as my own all such modifications and adaptions as fall within the scope of the appended claims.

I claim:

1. A device of the character described comprising a housing structure positioned in a highway at one side of a railway track across which said highway extends, a pair of 130

vertically-swingable gate arms extending from said housing and movable from raised, inactive position to lowered, passage-obstructing position, a shaft rotatably supported in said housing, motion-transmitting means connecting said shaft with said gate arms for raising and lowering said arms, means tending to rotate said shaft, and means releasably holding said shaft against rotation.

2. A device of the character described comprising a housing structure positioned in a highway at one side of a railway track across which said highway extends, a pair of vertically-swingable gate arms extending from said housing and movable from raised, inactive position to lowered, passage-obstructing position, a shaft rotatably supported in said housing, motion-transmitting means connecting said shaft with said gate arms for raising and lowering said arms, means tending to rotate said shaft, a control disc secured to said shaft, having oppositely-extending stop projections on its periphery spaced 180° apart and out of alignment with each other, a pair of electro-magnets having armatures respectively extending in the paths of movement of said stop projections when the electro-magnets are de-energized, electric circuits for operating said electro-magnets, said electric circuits being normally open and one of said electric circuits including a normally open switch adapted to be closed by the wheel of a railway car approaching said crossing on the track, another of said electric circuits including a normally open switch adapted to be closed by the wheel of the car as the latter traverses the track at the intersection of the track and the highway.

3. A device of the character described, comprising a housing structure positioned in a highway at one side of a railway track across which said highway extends, a pair of vertically-swingable gate arms extending from said housing and movable from raised, inactive position to lowered, passage-obstructing position, a shaft rotatably supported in said housing, motion-transmitting means connecting said shaft with said gate arms, means tending to rotate said shaft, a control disc secured to said shaft, having oppositely-extending stop projections on its periphery spaced 180° apart and out of alignment with each other, a pair of electro-magnets having armatures respectively extending in the paths of movement of said stop projections when the electro-magnets are de-energized, electric circuits for operating said electro-magnets, said electric circuits being normally open and one of said electric circuits including a normally open switch adapted to be closed by the wheel of a railway car approaching said crossing on the track, another of said electric circuits including a

normally open switch adapted to be closed by the wheel of the car as the latter traverses the track at the intersection of the track and the highway, said first electric circuit including a normally closed switch located between said normally open switch and the crossing and adapted to be operated by the wheel of a railway car traversing said track between said first-named switch and said crossing.

4. A device of the character described comprising a housing structure positioned in a highway at one side of a railway track across which said highway extends, a pair of vertically-swingable gate arms extending from said housing and movable from raised, inactive position to lowered, passage-obstructing position, a shaft rotatably supported in said housing, motion-transmitting means connecting said shaft with said gate arms for raising and lowering said arms, means tending to rotate said shaft, a control disc secured to said shaft, having oppositely-extending stop projections on its periphery spaced 180° apart and out of alignment with each other, a pair of electro-magnets having armatures respectively extending in the paths of movement of said stop projections when the electro-magnets are de-energized, two electric circuits for operating one of the said electro-magnets and a third electric circuit for operating the second electro-magnet, each of said first-named circuits including a normally open switch associated with a track rail at one side of the crossing, the respective normally-open switches being positioned at opposite sides of the crossing, and a pair of normally-closed switches associated with the track rail and respectively located between said first-named switches and the crossing, each of said switches being adapted to be actuated by the wheel of a railway car traversing the portion of the track rail with which said switch is associated, each of said normally-open switches adapted to be closed by the wheel of a railway car and each of said normally closed switches adapted to be opened by said railway car wheel, the circuit for operating the second electro-magnet including a normally-open switch associated with the track rail at the crossing and adapted to be closed by the wheel of a railway car as said car traverses the track at the crossing.

5. A device of the character described comprising pivoted gate members at opposite sides of the track at a railway crossing, means for raising and lowering said gate members, electro-magnetic control means for controlling the operation of said gate-operating means, electric circuits including switch members adapted to be actuated by the wheel of a railway car approaching the crossing on said track from either of two opposite directions for closing said switch,

other normally-closed switches positioned adjacent to said first-named switches and adapted to be operated by the wheel of a car passing from said crossing toward said first-named switches to render said first-named switches ineffective to close said circuit, and a normally-open switch located at said crossing and adapted to be actuated by the wheel of a car traversing the rail at the crossing to close a circuit for raising said gates.

6. A device of the character described comprising pivoted gate members at opposite sides of the track at a railway crossing, means for raising and lowering said gate members, electro-magnetic control means for controlling the operation of said gate-operating means, electric circuits including switch members adapted to be actuated by the wheel of a railway car approaching the crossing on said track from either of two opposite directions for closing said switch, other normally-closed switches positioned adjacent to said first-named switches and adapted to be opened by the wheel of a car passing from said crossing toward said first-named switches to render said first-named switches ineffective to close said circuit, a normally-open switch located at said crossing and adapted to be actuated by the wheel of a car traversing the rail at the crossing to close a circuit for operating the said electro-magnetic means to raise said gate members, said electro-magnetic control means including electrically connected members for operating the gates, which are located at opposite sides of the track, simultaneously and in the same manner.

7. In a device of the character described, a housing structure in the middle of the highway at one side of the railway track, said housing having vertical slots in the side walls thereof, a pair of gate arms extending through said slots into the housing and pivotally supported adjacent to their inner ends for swinging movement between raised and lowered positions, a shaft rotatably supported in the housing, the axis of the shaft being parallel to the axes of the swinging movements of said gate arms, motion-transmitting means connecting the inner ends of said gate arms and said shaft whereby said gate arms will be raised and lowered during each complete rotation of said shaft, a drum secured on said shaft, gravity means associated with said drum in cooperation with the latter to rotate said shaft, and means for controlling the rotation of said shaft, said controlling means including a disc mounted on the shaft having a plurality of spaced radial stop projections on its periphery, electro-magnets having armatures adapted to extend in the path of movement of certain of said stop projections when the electro-magnets are de-energized, and an alarm adapted to be actuated by one of said projections when said disc rotates from a certain position.

cooperation with the latter to rotate said shaft and means for controlling the rotation of said shaft.

8. In a device of the character described, a housing structure in the middle of the highway at one side of the railway track, said housing having vertical slots in the side walls thereof, a pair of gate arms extending through said slots into the housing and pivotally supported adjacent to their inner ends for swinging movement between raised and lowered positions, a shaft rotatably supported in the housing, the axis of the shaft being parallel to the axes of the swinging movements of said gate arms, motion-transmitting means connecting the inner ends of said gate arms and said shaft whereby said gate arms will be raised and lowered during each complete rotation of said shaft, a drum secured on said shaft, gravity means associated with said drum in cooperation with the latter to rotate said shaft and electro-magnetic means for controlling the rotation of said shaft.

9. In a device of the character described, a housing structure in the middle of the highway at one side of the railway track, said housing having vertical slots in the side walls thereof, a pair of gate arms extending through said slots into the housing and pivotally supported adjacent to their inner ends for swinging movement between raised and lowered positions, a shaft rotatably supported in the housing, the axis of the shaft being parallel to the axes of the swinging movements of said gate arms, motion-transmitting means connecting the inner ends of said gate arms and said shaft whereby said gate arms will be raised and lowered during each complete rotation of said shaft, a drum on said shaft, gravity means associated with said drum in cooperation with the latter to rotate said shaft, and means for controlling the rotation of said shaft, said controlling means including a disc mounted on the shaft having a plurality of spaced radial stop projections on its periphery, electro-magnets having armatures adapted to extend in the path of movement of certain of said stop projections when the electro-magnets are de-energized, and an alarm adapted to be actuated by one of said projections when said disc rotates from a certain position.

JOHN KINGSBURY WEST.
